TREATMENT OF WORK WITH SOLVENTS

Clarence F. Dinley, Detroit, Mich., assignor, by
mesne assignments, to Solvent Machine Company,
trustee, Detroit, Mich., a corporation of
Michigan

Application May 15, 1934, Serial No. 725,733

14 Claims.

(Cl. 87—8)

This invention relates to the treatment of work with solvents for such purposes as cleaning and degreasing, and to the use of volatile solvents; and especially to the cleaning of metal parts in preparation for plating. For the purposes of the invention, various solvents whose vapors are heavier than air are especially advantageous, such as benzine, benzol, and chlorinated solvents like carbon tetrachloride, trichloromethane, tetrachloromethane, dichlorethane, tetrachlorethane, trichlorethylene, and tetrachlorethylene, whose vapors are uninflammable. In thus cleaning such metal parts, it is commonly most advantageous to treat them mainly in boiling liquid solvent, rather than in the solvent vapor, and to minimize the vapor layer above the liquid solvent as far as possible; although in some cases the work may be satisfactorily cleaned in the solvent vapor, without immersion in liquid solvent or spraying therewith, or the like. My novel apparatus for such work accomplishes the treatment in a very simple, compact, and convenient manner. In certain aspects my apparatus may be regarded as an improvement of that disclosed in my Patent No. 1,942,355, granted January 2, 1934.

In preparing metal parts for plating, their surfaces are buffed with stearic buffering compounds (comprising abrasive like pumice and rouge mixed with grease such as tallow),—which reduces the unevenness of their surfaces,—and then precleaned. One way of precleaning is to dry-buff or "color" the work: this, however, is laborious, and entails hand scrubbing to remove buffering compound and lint from the crevices, if the work has retentive crevices. Another method of precleaning is by electro-alkali cleaner, followed by hand scrubbing. Still another method is to preclean in a heated oleaginous solvent, like gasoline, benzine, etc., and then in an electro-alkali cleaner. This method involves considerable loss of solvent, and serious fire hazard, although in itself fairly successful.

By precleaning with chlorinated solvents in accordance with my invention, such operations as hand coloring and hand scrubbing are avoided, as well as the fire hazards of inflammable solvents like gasoline, benzine, etc. My method is also very economical, reducing the loss of solvent. When the chlorinated solvent is kept free of water and fairly clean, use of an electro-alkali cleaner is unnecessary; but when it becomes substantially contaminated with the matter removed from the work in cleaning, so that contamination amounts to as much as 15% by

volume, the work must afterward be lightly cleaned in an electro-alkali cleaner. Even so, however, the time required for the final electro-alkali cleaning is greatly reduced, production can be increased, and there is considerable saving of electrical energy.

Using this last procedure, I have found that if the work is not transferred from the chlorinated solvent treatment to the electro-alkali cleaner right away, the residue left on its surface after the chlorinated solvent treatment tends to "set up", thus becoming harder to remove in the electro-alkali cleaner bath. This is because the water of condensation, which unavoidably collects in a layer on the top of the chlorinated solvent bath, "water-spots" the work. However, I have discovered that by a small protective addition to the chlorinated solvent bath, as of fat like lard or tallow, this can be overcome: i. e., the lard or tallow coats the work cleaned in the bath of boiling chlorinated solvent in a very thin film, and the water on the bath cannot penetrate this film and spot the work when the latter is removed from the bath of chlorinated solvent.

In the drawings, Fig. I is a side view of one form of apparatus for the purposes of my invention.

Fig. II shows a transverse section through the apparatus of Fig. I, taken as indicated by the line and arrows II—II in Fig. I.

Fig. III is a side view of another form of apparatus, partly in vertical mid-section.

Fig. IV is a plan view of the apparatus shown in Fig. III.

Fig. V shows a horizontal section taken as indicated by the line and arrows V—V in Fig. III; and,

Fig. VI is a fragmentary sectional view on a larger scale than Figs. III—V, taken as indicated by the line and arrows VI—VI in Fig. IV.

The apparatus shown in Figs. I and II comprises a treating vessel or enclosure 10 open upward for the introduction and removal of the things or work to be treated, but closed to exclude air and retain the solvent vapor. The enclosure or casing 10 forms a tunnel-like chamber with upward sloping entrance and exit ends 11 and 12, and an approximately horizontal mid-body 13; and its lower portion serves as a tank 50 or vat for the liquid solvent. Along the upper portion of the casing 10 is an (overhead) conveyor 15 for the articles or work, which conveyor 15 is here shown as comprising a two-rail track 16, 16, (of angle sections) and a plu-

rality of double-roller trolley carriers 17, provided with supporting means such as trays 18, for carrying the articles or work through the treating chamber 10. Means may be provided 5 for moving the trolleys 17 along the track 16 at suitable intervals, such as a conveyor chain 20, some of whose links may be pivoted together by the trolley roller axes or spindles 21. The conveyor 15 may in practice form part of the 10 general conveyor system of a plant or plant-department where the apparatus is used. At the upward-sloping open casing ends 11, 12, the track 16, 16 likewise bends and slopes upward. Between the end openings at 11, 12, the casing 15 top or roof 22 is closed except for a longitudinal trolley slot 23 between the angle tracks 16, 16, which are secured to upturned roof flanges 24, 24 that coact with said angles 16, 16 to form a 20 sort of monitor structure.

20 The lower mid-portion 13 of the casing 10 has means for heating and vaporizing (boiling) the solvent, such as longitudinal steam pipes 25, 25 at either side thereof, below the path or sweep of the conveyor carriers 17. The heating means 25, 25 are high enough above the bottom of the vessel at 10 to afford a relatively tranquil settling zone or sump therebeneath for dirt, lint, or other matter from the work. As shown, the lower portion of the vessel 10 is contracted, with inward sloping side walls at 26, 26, to form a reduced longitudinal trough-like sump 27 for the sediment between the heating pipes 25, 25, which overlie the sloping bottom shoulders 26, 26. Separate provision is made for heating the contents 30 of the settling zone or sump 27, as by means of a steam jacket 28 on its bottom wall. The sump 27 has a drainage outlet from its low point, controlled by a valve 29.

Accumulation of vapor in the apparatus to the 40 point of overflow or escape from the open tunnel ends at 11, 12 and from the trolley slot 23 in the roof 22 may be prevented by condensing the vapor. As shown in Fig. II, part at least of the condensing means may be interposed between the 45 work on the carriers 17 and the outer opening of the roof-slot 23, so as to prevent access of solvent vapor to the slot 23. In the present instance, there are two thin flat cold-water jacket sections or units 30, 30, at opposite sides of the 50 trolley "shanks" which extend up through the slot 23 and travel therein. The condensers 30, 30 need not be right up against the roof 22, but may (as here shown) be as low down in the casing 10 as consists with their clearing the work on 55 the carriers 17. The condenser sections 30, 30 may be supported and secured on brackets 31, 31 fixed to the casing sides, and may slope outward toward the sides. Collecting troughs 32, 32 are mounted on the casing sides under the outer 60 lower edges of the sections 30, 30, to catch the dripping condensate. As shown, there are drain pipes 33 from the low points of the troughs 32, controlled by valves 34, and delivering into (external) liquid storage tanks 35 at either side of the 65 apparatus. Thus the purified condensate is collected by the troughs 32, 32 separate from the solvent heated by the pipes 25, in which work has been cleaned, and can be stored and kept clean in the tanks 35. From these tanks 35, the 70 solvent may be returned to the lower portion of the apparatus through pipes 36 controlled by valves 37.

A mode of operation of this form of apparatus is as follows:

75 If work is to be cleaned by immersion in hot

liquid solvent, the apparatus is filled with liquid solvent about up to the level 1, about $\frac{1}{2}\%$ of lard or tallow or the like being preferably added to the solvent. The valve 29 is, of course, closed. The heating pipes 25, 25 are supplied with steam, while cold water is circulated through the cooling units 30, 30. No steam or heat is supplied to the jacket 28. The valves 29, 34, 37 are closed. The liquid solvent is heated, by the pipes 25, 25, and kept at a suitable temperature for cleaning 10 the work. The vapor thus evolved is condensed by the cooling units 30, 30, and thus kept from rising above them, and from reaching the openings at 11, 12 and 23. When the liquid solvent is hot enough, work may be passed through it 15 on the carriers 17 by means of the conveyor system 15, and cleaned by the solvent and washing action of the liquid. Grease and oil dissolve 20 in the solvent, while solid particles of grit, buffering compounds, lint, or the like wash off and settle 25 by gravity into the tranquil region or zone below the heating pipes 25, 25, where the liquid is not boiling or being agitated by the heat. Thus such matter is kept out of the liquid circulation in 30 the vessel at 10, and has no chance to settle on 35 the cleaned work, or to come in contact with it and adhere to it. The solvent vapor condensed by the condensers 30 runs down into the troughs 32 and overflows back into the pool of hot solvent 40 in the vessel 10,—the valves 34 being closed. 45

If the work is to be cleaned with solvent vapor instead of by contact with liquid solvent, then the solvent level will be about at 1', just below the carrier trays 18.

When dirt and grease have accumulated in the 55 apparatus up to the pipes 25, or as much as deemed desirable, the passage of work therethrough is stopped, and the valves 34 are opened,—the valves 29 and 37 still remaining closed. The supplies of steam and of condensing water being continued, and hotter steam supplied if necessary, the solvent boils, and condensate from the troughs 32 drains into the storage tanks 35, until all the solvent in the apparatus has been thus purified and stored in 60 these tanks,—excepting, of course, that below the heating pipes 25. Thereupon steam may be shut-off from the pipes 25 and turned into the bottom jacket 28; and thus the distillation of solvent may be continued and completed. When 65 all the solvent (or as much as desired) has thus been purified, the steam (and cooling water) supply may be shut-off altogether, and the drain valve 29 may be opened to draw off the accumulated sludge of oil, grease, and dirt from the 70 sump 27. If desired, of course, a certain amount of solvent may be left in this sludge, to make it liquid enough to be drawn off easily; and in this case it may not always be necessary to use the heating jacket 28. The sump 27 and the interior 75 of the apparatus may, of course, be further cleaned mechanically, or washed out with any suitable solvent or other fluid. As shown in Fig. II, the solvent return pipes 36 from storage tanks 35 open into the vessel 10 above the settling 80 zone in its lower portion, so that purified condensate from the tanks may be used for washing out the settling zone. Thereafter the valve 29 is closed, and the valves 37 are opened to return the purified solvent into the apparatus; whereupon the valves 34 and 37 are all closed; and the apparatus is ready to restart operation as 85 already described.

The apparatus shown in Figs. III-VI comprises a treating vessel, tank, vat, or chamber 90 95

of a hollow configuration in plan, with outer shell 51, inner shell 52, and bottom 53, extending around an inner space 54 within the shell 52,—which space 54 may be provided with a bottom 55 and serve as a reservoir or storage tank for solvent. Near and above the top of the vat 50 are double-walled cooling water jackets 56, 57, shown as forming upward extensions of the shell walls 51, 52, but offset outward and inward from them, respectively. The apparatus may preferably have a removable cover or lid 58 over its top, shown as a metal plate whose margin engages an angle flange lip 59 on an outer upper shell wall 60, extending above the jacket 56. In the cover 58 there may be a charging or loading and unloading opening 61, for the introduction and removal of work into and from the vat 50. Work may be carried along in a closed circuit through the vat 50 by a moving conveyor or carrier 62, preferably mounted on the cover 58 and removable with it.

The particular apparatus here illustrated is of a circular design; its vat or chamber 50 is of an annular configuration; and its work-conveyor or carrier 62 revolves as a turntable. This revolving carrier or turntable 62 is mounted on the lower end of an upright shaft 63 which extends up into an upper journal bearing 64 on the cover 58, and down into a lower step bearing 65 mounted on angle bars 66 fixed across the interior of the inner shell 52. The carrier 62 comprises an angle bar rim 67 and a diametrically extending channel 68 to which is welded the carrier hub 69, and whose ends are attached to angle bar chords 70, 70, whose ends are in turn fastened to the rim 67. The carrier 62 may be driven by an (electric) motor 73 mounted on the cover 58, and connected by a variable speed belt drive 74 and a worm reduction gearing 75 to an upright shaft 76 which extends down through the cover 58 to a spur pinion 77 meshing with a spur gear 78 on the carrier shaft 63, between the carrier and the cover.

In the apparatus, the work may be supported by removable plating racks 80 whose supporting hooks 81 take into holes in the horizontal legs of angle brackets or stirrups 82 adjustably secured to the outer angle-rim 67 of the carrier 62 by screws 67a extending through vertical slots 67b in the upright bracket legs, and taking into the rim 67. Racks 80 with their charges of articles to be plated may be hung on the carrier stirrups 82 and removed, one by one, as the stirrups 82 pass adjacent (beneath) the opening 61. As indicated in Figs. III and IV, each rack 80 comprises a vertical series of horizontal bars 85 mounted on an upright center rod 86, and provided with plating hooks 87. The rod 86 has a hook 88 at its upper end, by which the rack 80 can be handled,—as well as the supporting hook 81 already mentioned.

For heating the liquid solvent in vat 50 in ordinary operation, there are a couple of annular steam pipes 90, 91 coiled around the vat at a sufficient height above its bottom to allow a settling zone below for matter from the work. These pipes 90, 91 have steam supply connections 92, 93 at the rear of the apparatus (Fig. V), and also discharge connections 94, 95. For heating the contents of the vat 50 when below the level of the coils 90, 91 (for cleaning out purposes), the vat has a steam jacket 96 on its bottom, with stays 97 thereacross for resisting the internal pressure. Steam is supplied to the jacket 75 96 through a pipe 98 that extends about half

way around the jacket, where it terminates behind a baffle 99. Water of condensation, etc., is discharged from the jacket 96 through a pipe 100.

Cooling water is circulated through the annular cooling jackets 56, 57, for the purpose of chilling and condensing the solvent vapor evolving from the hot liquid solvent in the vat. For the outer jacket 56, there are supply pipes 101, 101 which enter the jacket at diametrically opposite points close to its bottom, and discharge pipes 102, 102 which are connected to the jacket near its top, at diametrically opposite points midway between the pipes 101, 101. For the inner jacket 57, there is a supply pipe 103 entering the 15 jacket near its bottom and a diametrically opposite discharge pipe 104 connected to the jacket near its top. These pipes 103, 104 extend down through the inner reservoir 54 and out across through the vat 50 below the heating coils 90, 91. 20

The solvent vapor condensing on the cool inner walls of the jackets 56, 57 trickles down into annular collecting troughs 106, 107 between the upper margins of the vat walls 51, 52 and the inner walls of the jackets. The bottoms of these 25 troughs 106, 107 are formed by angle rings 108, 109 affixed to the inner and outer sides of the vat walls 51, 52, and the jackets 56, 57 are attached to the outer margins of the angles. From the troughs 106, 107, the condensed solvent ordinarily drains directly back into the vat 50 through holes 110, 110 in the trough walls 51, 52, which are ordinarily open, but can be closed by means of screw plugs 111, 112 as shown in Fig. IV. When the holes 110, 110 are closed, the 30 condensate can be drained from the troughs 106, 107 into the inner reservoir 54 through pipes 113, 114 controlled by valves 115, 116. From the reservoir 54, liquid solvent can be transferred or returned to vat 50 through a pipe line 117, which 40 as here shown extends up above the jacket 56 and in through the upper (outer) shell wall 60, and has interposed therein a (hand) pump 118 for pumping the liquid solvent over into the vat 50; a control valve 119; and a supply connection 45 120 with a control valve 121. As here shown, one of the drain pipes 114 takes into the lower portion of the pipe line 117, so that the latter performs a double function.

In the outer vat wall 51, there may be one or 50 more clean-out openings with removable covers or doors 122 secured thereto with fluid-tight joints.

In ordinary operation, the liquid solvent in the vat 50, standing about at the level L and containing about $\frac{1}{2}\%$ of lard or tallow, or the like, if desired, is heated by the steam coils 90, 91, and kept at a suitable temperature for cleaning the work. The carrier 62 is driven by the motor 73 (through the change speed and reduction 60 gearing 74, 75) at any suitable rate, such as $\frac{1}{2}$ to $1\frac{1}{2}$ R. P. M., and the racks 80, previously charged with articles to be cleaned, are loaded on the carrier and unloaded therefrom as the carrier stirrups 82 pass the cover opening 61. Between loading and unloading, each rack 80 may make one full revolution (or more) with the carrier 62. The hot solvent drains and dries from the hot articles almost immediately as each plating rack 80 is removed from the machine, 70 and the articles remain on the plating racks hot and dry, ready for plating.

The solid residues of dirt removed from the articles by the solvent, such as lint, grit, buffering compound, settle to the bottom of the vat 50, 75

below the coils 90, 91. When the accumulation of such solids reaches the coils, cleaning of the apparatus and of the solvent is advisable,—since the solvent has also become contaminated by the grease dissolved from the articles cleaned. For this purpose, after steam has been temporarily shut off from the coils 90, 91, the drain holes 110, 110 are closed with the plugs 111, 112, and the valves 115, 116 in pipes 113, 114 are opened, to allow the purified condensate to drain from troughs 106, 107 into reservoir 54. Steam having been re-admitted to the coils 90, 91, solvent is distilled over into the reservoir 54 till its surface comes down to the coils,—when, if desired, steam is shut off from them and admitted to bottom jacket 96, and distillation continued till substantially all solvent has been distilled over. Then clean-out door(s) 122 are opened, and the residue of oil, buffering compound, lint, etc. is removed from the bottom of the vat. The apparatus may then be restored to ordinary operating condition (as explained above), the purified solvent pumped back from reservoir 54 into vat 50, and loss of solvent made up by addition of fresh solvent, through cover opening 61 or connection 120.

Having thus described my invention, I claim:

1. Apparatus of the character described, for treating articles or work with volatile solvent whose vapor is heavier than air, comprising a solvent vessel or vat provided with means of drainage from its bottom, heating means for heating the liquid solvent therein located high enough above the bottom of the vessel to afford a settling zone for matter from the work below said heating means, condensing means at a higher level of the vessel for condensing solvent vapor evolved therein, means for collecting and means for storing the condensate, and returning the stored condensate to said vessel above its said settling zone, so that the purified condensate may be used for washing out said zone.

2. Apparatus of the character described, for treating articles or work with volatile solvent whose vapor is heavier than air, comprising a solvent vessel or vat having a contracted lower portion or sump provided with means of drainage at its bottom, heating means in the vessel located above and aside from said sump high enough above the bottom of the vessel to afford a settling zone for matter from the work below said heating means, condensing means at a higher level of the vessel for condensing solvent vapor evolved therein, means for collecting and storing the condensate, and means for returning the stored condensate to said vessel above its said sump, so that the purified condensate may be used for washing out said sump.

3. Apparatus of the character described, for treating articles or work with volatile solvent whose vapor is heavier than air, comprising a solvent vessel or vat having a contracted lower portion or sump provided with means of drainage at its bottom, heating means for heating the liquid solvent in the vessel above said sump, condensing means at a higher level of the vessel for condensing solvent vapor evolved therein, means for collecting and storing the condensate, means for returning the stored condensate to said vessel above its said sump, so that the purified condensate may be used for washing out said sump and means for heating the contents of said sump.

4. Apparatus of the character described, for treating articles or work with volatile solvent whose vapor is heavier than air, comprising a

solvent vessel or vat having a contracted lower portion or sump, heating means for heating the liquid solvent in the vessel located above and aside from said sump, condensing means at a higher level of the vessel for condensing solvent vapor evolved therein, and means for heating the contents of said sump.

5. In apparatus of the character described, for treating things or work therein with volatile solvent whose vapor is heavier than air, the combination of a treating vessel or chamber closed and covered over to exclude air and retain the solvent vapor, but open at its upper portion for the introduction and removal of work and also having a conveyor slot in its roof, an overhead conveyor supported above said slot and including means extending down through the slot and adapted to travel therein to carry work through the chamber, and condensing means extending along at either side of the path of said downward-extending means and interposed between the opening of said slot and the work carried by the conveyor, and preventing access of the solvent vapor to said slot.

6. Apparatus of the character described, for treating articles or work with volatile solvent whose vapor is heavier than air, comprising a solvent vat extending around an inner space, a cover therefor apertured for the introduction and removal of work into and from the vat, a moving carrier beneath the cover for the work in the vat, passing under the cover opening for loading and unloading therethrough, heating means for boiling the solvent in the vat located below the sweep of the carrier but high enough above the bottom of the vat to afford a settling zone for matter from the work below said heating means, condensing means at a higher level of the vat for condensing solvent vapor evolved therein, and means for heating the contents of said settling zone of the vessel below said first-mentioned heating means.

7. Apparatus of the character described, for treating articles or work with volatile solvent whose vapor is heavier than air, comprising a solvent vat extending around a central space, a cover therefor apertured for the introduction and removal of work into and from the vat, a moving carrier beneath the cover for the work in the vat, passing adjacent the cover opening for loading and unloading therethrough, and condensing means for the solvent vapor in the central space to the inside of the vat below the cover.

8. Apparatus of the character described, for treating articles or work with volatile solvent whose vapor is heavier than air, comprising a solvent vat extending around a central space, a cover therefor apertured for the introduction and removal of work into and from the vat, a moving carrier beneath the cover for the work in the vat, passing adjacent the cover opening for loading and unloading therethrough, and condensing means for the solvent vapor in the central space within and below the sweep of said moving carrier.

9. Apparatus of the character described, for treating articles or work with volatile solvent whose vapor is heavier than air, comprising a solvent vat extending around a central space, a cover therefor apertured for the introduction and removal of work into and from the vat, a moving carrier beneath the cover for the work in the vat, passing adjacent the cover opening for loading and unloading therethrough, condensing means for the solvent vapor in the central space

to the inside of the vat below the cover, and condensing means at the outer side of the vat at said cover opening.

10. Apparatus of the character described, for 5
treating articles or work with volatile solvent
whose vapor is heavier than air, comprising a
solvent vat extending around a central space, a
cover therefor apertured for the introduction and
removal of work into and from the vat, a moving
10 carrier beneath the cover for the work in the
vat, passing adjacent the cover opening for load-
ing and unloading therethrough, condensing
means for the solvent vapor in the central space
within and below the sweep of said moving car-
15 rier, and condensing means above the vat at
said cover opening, outside the sweep of said
moving carrier.

11. Apparatus of the character described, for
treating articles or work with volatile solvent
20 whose vapor is heavier than air, comprising a
solvent reservoir and a circumjacent solvent vat
with outer wall higher than its inner wall, a
cover over said vat and reservoir apertured for
the introduction and removal of work into and
25 from the vat, a moving carrier beneath the cover
for the work in the vat, passing adjacent the
cover opening for loading and unloading there-
through, and means for condensing, below the
cover but above the reservoir, the solvent vapor
30 evolving from the vat, with drainage of the con-
densate into said reservoir.

12. Apparatus of the character described, for
treating articles or work with volatile solvent
whose vapor is heavier than air, comprising a sol-
35 vent reservoir and a circumjacent solvent vat
with outer wall higher than its inner wall, a cover
over said vat and reservoir apertured for the in-
troduction and removal of work into and from
the vat, means for condensing, below the cover
40 but above the reservoir, the solvent vapor evolv-
ing from the vat, with drainage of the condensate
into said reservoir, and means for pumping the
condensed solvent from said reservoir back into
the vat.

13. Apparatus of the character described, for
treating articles or work with volatile solvent
whose vapor is heavier than air, comprising a
solvent reservoir and a circumjacent solvent vat
with outer wall higher than its inner wall, a re-
5 movable cover over said vat and reservoir, a
moving carrier for the work in the vat mounted
on the cover at its lower side and removable with
and by the cover, means for condensing below
the cover the solvent vapor evolving from the 10
vat, with drainage of the condensate into said
reservoir, and means for pumping the condensed
solvent from said reservoir back into the vat.

14. A method of cleaning articles or work in a
vessel with volatile solvent whose vapor is heavier 15
than air, accumulating matter from the work in
the vessel while avoiding contamination of work
with the accumulated matter, and periodically
distilling the used solvent, allowing the vessel to
be cleaned out, and recovering the solvent free 20
of the accumulated matter; which method com-
prises heating and vaporizing the liquid solvent
in the vessel at a zone or level sufficiently above
the bottom of the vessel, during the ordinary
operation of cleaning the work, to provide a 25
tranquil settling zone for the accumulation of
matter from the work in the lower portion of
the vessel, while condensing the solvent vapor
evolved by the heating of the solvent at a higher
level of the vessel than said heating zone; clean- 30
ing work in the vessel, while matter therefrom
accumulates in the settling zone; and as the
accumulation of settled matter substantially
reaches the heating zone, discontinuing the clean-
ing of work and distilling off the solvent from 35
said settling zone; while condensing the solvent
vapor evolved and collecting and storing the pu-
rified liquid condensate separate from the used
liquid solvent in the vessel, continuing the dis-
tillation until the used liquid solvent is boiled 40
away, and then discontinuing the distillation and
removing the residue from the vessel.

CLARENCE F. DINLEY.
